UNITED STATES PATENT OFFICE

CHRISTIAN SCHNEIDER AND FRANZ SABEL, OF NEUROESSEN, GERMANY, ASSIGNEES
TO I. G. FARBNENINDUSTRIE AKTIENGESELLSCHAFT, OF FRANKFORT-ON-THE-
MAIN, GERMANY, A CORPORATION OF GERMANY

GAS PRODUCER

Application filed November 19, 1928, Serial No. 320,407, and in Germany November 22, 1927.

The present invention relates to gas producers having a stationary grate and a rotary scraper removing the solid ashes by the action of the scraper through one or 5 more ash holes in the middle of the grate.

A great variety of grates and ash discharging devices are known in connection with gas producers which are operated with fuels tending to form clinker or which are 10 rich in ash constituents. Complete removal of the residues has to be ensured in conjunction with the best possible distribution of the gasifying agent, air or steam. Thus, for example, the employment of a traveling 15 grate has been proposed, which is specially adapted for removing ashes from and supplying air to producers which are operated on the principle of an eddying movement of the fuel bed.

20 We have now found that the ashes in gas producers with stationary grates and rotary scrapers can be removed efficaciously by adopting an arrangement for directing the said residues toward one or more central 25 ash holes by the action of the scraper.

For example, a scraper may be employed which has small obliquely disposed blades and is preferably actuated from below through the ash hole, the rotary movement 30 of said stirrer slowly pushing the clinkers and ash towards the centre, where they can be continuously or intermittently drawn off through a central pipe.

The accompanying drawing shows in vertical section in Figure 1 and in plan in Figure 2 an example of an arrangement according to this invention, but the invention is not restricted thereto. The hollow, preferably water-cooled, scraper *a*, *a*, is actuated from below by means of the hollow shaft *b* and pinion gear *c*, its rotational speed being regulated according to the dimensions and output of the producer, the speed being, for example, 0.5 to 1 metre per 40 minute for a circular gas producer with a diameter of 1.5 meters. Small obliquely disposed blades *f* push the ashes towards the central ash hole *d*, where the ashes are drawn off through a pipe *r*. The gasifying agent, 45 air and/or steam, is passed by pipes *g* and *i*

to below and through the grate and thus does not come into contact with the ashes. The hollow scraper *a* may be cooled by means of a cooling medium passed through it. The cooling medium is supplied by pipe 55 *k* and through the hollow shaft *b* into the scraper and leaves the latter by a passageway formed by a tube *h* surrounding the hollow shaft and is drawn off at *l*. The driving mechanism for the shaft and scraper 60 consists of the gear *c* which is driven by an electro-motor by means of a connecting gearing.

The drawing shows a flat grate, but it may also for example, be slightly dished in the 65 shape of a hopper, the ash hole being situated at the lowest point. The arms of the scrapers must, in this case, be adapted to conform to the shape of the grate. The height of the scraper arms above the grate 70 can be adjusted as desired by raising or lowering the shaft *b* on which they are mounted.

The scraper may also be constructed without the small, oblique blades, as for example 75 when fuel of the producer charge offers an unduly high resistance, the essential point being that the design of the scraper be adapted to push the ashes and residues towards the ash hole.

In comparison with gas producers provided with a stationary grate and a rotary scraper from which the ashes are removed through the grate itself or over its border, the above described construction has the great advantage that the ashes can directly 80 be removed from the producer without coming into contact with the inflowing gasifying agents, whereby any further formation of clinkers is avoided. Since the grate is inserted into the side walls of the producer 85 without interruption which is necessary when removing the ashes over the border of the grate, the obnoxious formation of fire at the border of the grate which greatly diminishes the quality of the gas produced, 90 is avoided, and the producer can be constructed more safely. By the construction according to the invention also the losses of fuel are reduced due to the smallness of the 95 ash holes.

Producers of the herein described kind are particularly suitable for the production of producer- or water-gas from small sized carbonaceous material in accordance with 5 the process described in the U. S. Patent No. 1,687,118, in which the air as well as the steam, if such be employed, are blown into the gas producer at such a velocity that the whole fuel is set in an up- and downward 10 whirling motion.

What we claim is:—

1. In a gas producer, a stationary grate closely joining the side wall of the producer and provided with a central opening, a pipe 15 passing into said opening, a rotatable shaft within said pipe, a scraper rigidly mounted on said shaft rotatable above said grate and adapted to push ashes through said central opening into said pipe, a mechanism for 20 rotating said shaft and scraper, and means for supplying a gasifying agent to below and through said grate.
2. In a gas producer, a stationary grate closely joining the side wall of the producer 25 and provided with a central opening, a pipe passing into said opening, a rotatable hollow shaft within said pipe, a hollow scraper rigidly mounted in said shaft rotatable above said grate and adapted to push ashes 30 through said central opening into said pipe, means for passing a cooling medium through said hollow shaft and said hollow scraper, a mechanism for rotating said shaft and scraper, and means for supplying a gas- 35 ifying agent to below and through said grate.

In testimony whereof we have hereunto set our hands.
